FISH LURE

Jim Z. Nishioka, John Day, Oreg.

Application February 24, 1959, Serial No. 54,711

Term of patent 14 years

(Cl. D31—4)

Fig. 1 is a side elevation of a fish lure embodying my new design;

Fig. 2 is a top plan view thereof, the swivel being omitted for convenience of illustration;

Fig. 3 is a side elevational view thereof with the body of the lure rotated 180° from its position in Fig. 1;

Fig. 4 is a bottom plan view of Fig. 1, the swivel and bead being omitted for convenience of illustration; and

Fig. 5 is a side elevational view thereof with the body of the lure rotated 90° from its position in Fig. 3.

I claim:

The ornamental design for a fish lure, substantially as shown.
